US00D926153S

(12) **United States Design Patent** (10) **Patent No.:** **US D926,153 S**
Yan (45) **Date of Patent:** **** Jul. 27, 2021**

(54) **WIRELESS HEADSET**

(71) Applicant: **SHENZHEN FUSHIKE ELECTRONIC CO., LTD**, Shenzhen (CN)

(72) Inventor: **Xiaohuang Yan**, Shenzhen (CN)

(73) Assignee: **SHENZHEN FUSHIKE ELECTRONIC CO., LTD**, Shenzhen (CN)

(**) Term: **15 Years**

(21) Appl. No.: **29/728,511**

(22) Filed: **Mar. 19, 2020**

(51) LOC (13) Cl. **14-01**

(52) U.S. Cl.

USPC **D14/206**; D14/226

(58) **Field of Classification Search**

(57) **CLAIM**

The ornamental design for a wireless headset, as shown and described.

DESCRIPTION

FIG. 1 is a front top and right perspective view of a wireless headset showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawing depict portions of the wireless headset that form no part of the claimed design.

1 Claim, 7 Drawing Sheets
